PADLOCK

Samuel C. Slaymaker, Lancaster, Pa., assignor to
The Slaymaker Lock Company, Lancaster, Pa.,
a corporation of Pennsylvania

Application April 16, 1936, Serial No. 74,717

9 Claims. (Cl. 70—108)

This invention relates to improvements in locks, and more particularly to padlocks, with reference to that class of such devices comprising a sliding shackle within a lock casing.

5 It aims to provide an improved lock adapted for general use, which can be made and sold at a reasonably low cost.

Among the several objects of the invention, the primary purpose is to produce an especially 10 strong, dependable and durable lock, having a simplified structure and operative mechanism, capable of being assembled easily and quickly with little need of adjustment or regulation.

Another primary object is to provide a lock in 15 which the operative parts are retained securely in place with protection against rupturing, distortion and throwing out of function by attempts to break or force it open.

Additional objects, as well as the general concept and improvement features of the invention, will be made to appear from the following description with reference to the attached drawing illustrating one practicable form and embodiment of 20 the same already in commercial production.

25 In said drawing:

Fig. 1 is a front face elevation of a padlock comprising the invention;

Fig. 2 is a corresponding view of the same with the front face member removed to reveal its operative parts, shown in locked position;

Fig. 3 is an inverted plan view of the removed front face member, as if swung from Fig. 2 like the page of a book would be turned;

Fig. 4 is a view similar to Fig. 2 showing the 35 positioning of parts upon insertion of an opening key;

Fig. 5 is a view in longitudinal section through the lock casing, showing the parts in opening position with turning of the key;

40 Fig. 6 is an end-wise elevation of the lock shackle, with an associated element shown in fragmentary section;

Fig. 7 is a transverse section taken on the lines 7—7 of Figs. 1 and 2;

45 Fig. 8 is a lower-plane section taken on the lines 8—8 of the same figures;

Fig. 9 is an enlarged cross-section of the lock tumbler barrel or cylinder, illustrating a detail; and

50 Fig. 10 is an elevation of the open casing, with the locking mechanism and other parts removed to show its interior formation.

The illustrative lock includes a casing 11 of rectangular block form, having lateral curvatures 55 giving it an oval shape in cross section. This casing is cast or molded in a single piece of strong metal and comprises a hollow or cavitated body of substantial wall thickness, with an opening in the front portion making it effectually open-faced. In the inner wall of the casing, a thick-

ening abutment shoulder 11^a is formed at the top right and left corners, and a similar but longer abutment 11^b is formed along one side—in this instance the right side—to the corresponding bottom corner, leaving a space between it and the first-named abutment at that side. A fourth abutment 11^c is formed in the remaining bottom corner. These several abutments serve to reinforce and greatly strengthen the casing. In addition, they advantageously serve other purposes 10 that will later appear, pursuant to which the three first described abutments are in this instance made surface level with each other. In the top of the casing, apertures 12 and 12' are provided to receive a shackle, one being extended through 15 the spaced abutments 11^a and 11^b at one side and the other extending only partially through the single abutment 11^c at the opposite side, so as respectively to accommodate the longer and shorter arms of the shackle.

The opening in the front face of the casing, indicated by 13, is rectangular in this instance, conforming to the shape of the casing. Said opening is closed, when the locked parts are assembled, by a face plate 14 fitting thereinto. 20 This plate is a strong metal member of substantial thickness, having the peculiar form illustrated in Fig. 3, with flat surface portions 14^a and 14^b resting respectively on the level abutments 11^a and 11^b, and a ridge 14^c resting on the abutment 11^c of the casing, so as to be firm and solid in position. A boss 14^d formed on its inner side extends through an opening 15 in the abutment 11^b for a purpose which will be described presently. The plate and casing together form 25 configurative cradle spaces or beds for the operative parts of the lock so as to maintain them properly tight and secure. Said cover plate is fastened in place by crimping or swaging the surrounding edges of the casing over the same, the opposite two parallel edges 11' represented being ordinarily quite sufficient for the purpose.

The shackle secured in the casing comprises the usual U-shaped member 16 of highly tempered steel, having its longer arm 16^a fitting in the 45 extended aperture 12 and its shorter arm 16^b fitting into the abbreviated aperture 12'. Guidably journaled to slide and swivel in the two abutments 11^a and 11^b, said longer arm of this shackle is formed with a recess 17 at its end into which 50 the boss 14^d extending through the opening 15 engages to limit the outward slide movement by a shoulder striking thereagainst, said recess merging into a reduced annular or groove portion 16^c receiving the boss all the way around so 55 as to allow the arm to swivel while still retained by said boss in the outward limit. Said longer arm is also formed with detents 18 in opposite sides, at the point of spanning the space 19 between the aforementioned abutments 11^a and 11^b, 60

when in the locked or fully inserted position. The purpose of these will appear presently. A spring 20 applied in the receiving aperture of this arm so as to tension against its end serves to 5 eject the shackle with a "snap" action when it is released from the locked position.

Inside the casing, a pawl comprising a spring member 21 of hair-pin form provides the locking element. This pawl or member is disposed cross-wise of the casing below the top corner abutments, with its legs 21^a and 21^b straddling the longer arm of the shackle and engaging normally in the detents 18 of the same (see Fig. 7). Its spring action tends to press the two legs together and 10 so keeps it firmly engaged with the shackle. It is held in the casing by the configurative formation of the latter and its cover plate, there being no independent fixing or fastening means therefor since such is unnecessary. While some equivalent other form of pawl might possibly be substituted satisfactorily for this spring member, the one described is preferred because it requires only a spread movement and acts as two pawls, being 15 thus a stationary double-acting member.

Also in the casing is a disc tumbler cylinder 22, disposed longitudinally of the same, and working in a retaining bed or cradle formed by the casing and cover plate. This cylinder is adapted to turn in a clockwise direction as viewed in side 20 elevation—or counterclockwise as viewed in the sectional Figs. 7 and 8—and carries an oval-shaped boss 22^a on its inner end extending between the legs of the spring member 21 so as to spread said legs apart when the cylinder is turned. 25 Its other end fits into a key hole 23 in the bottom of the casing and presents a slot through which to insert a key. Arranged in the body of the cylinder are a plurality of disc tumblers 24, normally projecting laterally over a shoulder 25 (see Figs. 2 and 8) formed in the abutment 11^b or wall of the casing, so as to prevent the cylinder from turning in the intended direction by striking thereagainst. An overextending ridge 26 formed in the cover plate similarly prevents 30 turning in the opposite direction, and a small shoulder 27 formed on the under side of the cylinder itself so as to strike against an edge 28 in the cradling wall of the casing supplements this latter preventative provision. Said disc tumblers are held normally in the projecting position by individual expansion springs 29 housed in 35 the cylinder and pressing lightly against lug-portions 24^a provided thereon (see Fig. 9). Each, of course, moves in a slide-way and has a central slot 30 registerable with the key slot of the cylinder.

Thus the locking and operative mechanism within the casing comprises simply a pawl-latch member and a disc cylinder, which latter is rotatable one way by a key. There are no other parts in the casing and no accessory means for holding the parts in place.

The key slot 31 of the disc tumbler cylinder is, of course, provided with the usual key guard (not shown). A proper key 32 fitted thereto retracts the tumblers as it is inserted, but does not hold them all retracted simultaneously until thrust the full way in. In such position, illustrated in Fig. 4, the tumblers are freed from 50 the shoulder 25 so as to allow the cylinder to turn. This turn is effected by turning the key, still full way in the cylinder, to the right. It is limited to a quarter circle, however, by a small shoulder 33 formed on the upper side of the cylinder, which strikes a shoulder 34 formed in

the abutment 11^b or wall of the casing at the bottom end.

Fig. 5 illustrates the positioning of the parts at the limit of the cylinder's opening or unlocking turn. At the completion of the turn, or just before, the boss 22^a on the inner end of the cylinder is swung sufficiently to spread the legs of the spring member 21 out of engagement with the detents of the shackle arm, whereupon the shackle is released and expelled by spring 20 sufficiently to be swung out on its swivel axis. Relocking is effected by pushing the shackle back in and turning the cylinder back to the original position, or simply by pushing the shackle back into place and withdrawing the key. The lock is 15 adapted to "snap closing" and when the key is withdrawn, the cylinder and tumblers tend to return to normal position, the first by action of the spring member 21 on its boss, and the second by action of their individual springs 29. The 20 shackle is effectually locked in place as soon as the legs of the spring member 21 reengage in the detents of its swivel arm, even though the cylinder might not be returned fully to its normal position with the tumblers overextending the 25 shoulder 25.

As the foregoing description makes the operation of the lock entirely clear, it is unnecessary to describe it in further detail. The lock, of course, operates essentially the same as others of 30 its kind and the novelty resides in the form of its casing and cover plate, and in the form of the shackle, combined with the inner operative or mechanism parts, all functioning interdependently. The improvement features and advantages of the lock so provided will be apparent to those familiar with the art.

Obviously, various changes may be made in the form and arrangement of the different parts, in different combinations and sub-combinations 40 of relation to each other, without departing from the spirit and scope of the invention. Therefore, the appended claims are not intended to limit the invention to the specific form and arrangement shown and described.

Having thus described my invention, what I claim as new and desire to secure by Letters Patent of the United States is:

1. A padlock, comprising a metal casing formed to receive a shackle and having an opening in 50 its face, a shackle extending into the casing with an arm journalled in a thickened interior wall portion thereof, and a metal cover plate secured in said opening having a boss extending through an opening in said thickened inner wall portion 55 into engagement with a recess in said shackle arm to prevent the shackle being withdrawn beyond a predetermined limit.

2. A padlock, comprising a metal casing formed with integral abutments in its inner wall 60 corners, one of said abutments being extended partially along one side, and with an opening in its front face, a shackle fitting into the casing with one of its arms journalled in the corner and extended abutments at one side, and a cover 65 plate fitted in said face opening having a boss extending through an opening in said side extended abutment into engagement with a recess in the shackle arm so as to limit the latter's outward withdrawal; said cover plate being fastened 70 in place with an inward bearing upon said corner abutments.

3. A padlock, comprising a metal casing formed with an opening in its face and with integral abutments in its inner wall corners, one of said 75

abutments being extended partially along one side, a shackle fitted in the casing having one arm journalled in the corner and extended abutments at one side, a metal cover plate fitted in the opening in the face of the casing and formed with an inner boss extending through an opening in the extended side abutment into a recess formed in the shackle arm so as to limit the outward movement of the latter, said cover plate being secured in said opening, a pawl member engaging the shackle within the casing, and a key-turned disc tumbler cylinder moving said pawl to disengage the shackle; the casing and the cover plate together forming configurative cradle spaces or beds retaining the pawl and cylinder members in place.

4. A padlock, comprising a metal casing formed with an opening in its face and with integral thickening and reenforcing walls abutments in each of its inner wall corners, one of the same being extended partially along one side leaving a space between it and the other corner abutment at that side, a shackle fitted in the casing with one arm slidably journalled in the corner and extended abutments at said one side, a metal cover plate fitted in the opening in the face of the casing and formed with an inner boss extending through an opening in the extended side abutment into a recess formed in the shackle arm so as to limit the slide movement of the latter, said cover plate being secured in said opening with an inward bearing upon said corner abutments of the casing, a spring pawl member engaging the shackle arm within the casing between said extended and adjacent corner abutments at one side, and a key-turned disc tumbler cylinder operating said pawl to disengage the shackle by partial rotation in one direction permitted with key insertion thereinto; the casing and the cover plate together forming configurative cradle spaces or beds retaining the spring pawl and cylinder members in place.

5. A padlock, comprising a casing consisting of a cavitated metal body formed with an opening in its face and with inner integral wall corner abutments, one of which is extended along one side, a shackle fitted in the casing with one arm journalled in the corner and extended abutments at one side, a metal cover plate fitted in the face opening of the casing and having a boss extending through an opening in the extended side abutment into a recess formed in the shackle arm so as to limit the outward movement of the latter and still allow the same to swivel in the outward position, said cover plate being secured in said opening with an inward bearing rest upon said corner abutments of the casing, a spring member having pawl portions engaging in opposite sides of said shackle arm within the casing, and a key-turnable disc tumbler cylinder having a boss working between the pawl portions of the spring member to spread them so as to disengage the shackle arm when the cylinder is turned in a predetermined direction by the operating key; said cylinder being normally unturnable and said casing and cover plate together forming configurative cradle spaces or beds retaining the latching spring member and cylinder in place without independent fastening means.

6. A padlock, comprising a casing consisting of a cavitated metal body formed with an opening in its face and with integral shoulder abutments in its inner wall corners, one of the same being extended along one side, a shackle fitted in the cas-

ing with one arm journalled in the corner and extended abutments at one side, a metal cover plate fitted in the face opening of the casing and having a boss extending through an opening in the extended side abutment into a recess formed in the shackle arm so as to limit the outward movement of the latter and still allow the same to swivel in the outward position, said cover plate being secured in said opening with surrounding edge portions of the casing marginally overlapping the same and with an inward bearing upon said inner corner abutments of the casing, a spring pawl member having its legs straddling and engaging detents formed in opposite sides of the shackle arm within the casing, and a key-turned disc tumbler cylinder having an extended boss working between the legs of the pawl member to spread them out of engagement with the shackle arm when the cylinder is turned by its key in a predetermined direction, said cylinder having a plurality of disc tumblers laterally extended over a shoulder in the casing to normally prevent the same from turning but retractable by the key to allow the same to turn; and said casing and cover plate together forming configurative cradle spaces or beds retaining the spring pawl and cylinder members in place without other fastening.

7. A padlock, comprising a cavitated metal casing formed to receive a shackle and having an opening in its face, a shackle extending into the casing with an arm journalled in a thickened interior wall portion thereof, a stop piece extended through said thickened wall portion into engagement with a recess in said arm of the shackle to prevent the same being withdrawn beyond a predetermined limit, and a metal cover plate secured in the opening in the face of the casing with a purchase rest bearing partially upon said thickened wall portion and partially upon other inner wall portions formed in the casing.

8. A padlock, comprising a solid metal casing cavitated to receive the operative parts and having an opening in its face, a shackle extending into the casing with an arm journalled in a thickened interior wall portion thereof, a stop pin fitted in said thickened wall portion in engagement with a recess in said arm to prevent the shackle being withdrawn beyond a predetermined limit, a spring pawl normally engaging the shackle in locked position, a tumbler cylinder adapted to actuate the pawl by key turn, and a metal cover plate secured in the opening in the face of the casing with an inward rest bearing upon said thickened and other wall portions of the casing.

9. A padlock, comprising a solid metal casing formed with recesses to receive a shackle and operative parts and having an opening in its face, a shackle extending into the casing with an arm journalled in a thickened interior wall portion thereof at one side, means disposed in said thickened wall portions in engagement with said arm to prevent the same being withdrawn beyond a predetermined limit, a spring pawl member normally engaging the arm in locking position, a tumbler cylinder adapted to actuate said pawl member to disengage the shackle arm with key turn, and a metal cover plate secured in the opening in the face of the casing, said cover plate being formed complementarily to the casing so as therewith to cradle the spring pawl and cylinder members and bearing inwardly upon rest portions formed in the interior walls of the casing so as to be held firm and solid in place.
